DRAFT RIGGING

William Watson Brinkley, Roanoke, Va., assignor
of twenty-four percent to E. Lee Trinkle, Jr.
and ten percent to Clarence M. Trinkle, Jr.,
both of Roanoke, Va.

Application July 2, 1935, Serial No. 29,543

2 Claims. (Cl. 213—40)

My invention relates to new and useful improvements in draft rigging for railway cars or the like and has for its principal object the provision of novel means to create a flexible movement between a locomotive and the adjacent cars, regardless of the number of cars coupled together to completely eliminate damaging impacts, shocks, or any form of rough handling, which is normally motivated by uncontrollable slack action and in carrying forward this object I provide a direct connection between the end sill or other stationary part of a car and an associated slideable draw bar shank to control the ordinary draft gear spring resiliency and in turn 10 to insure a uniform or flexible movement of the car or cars which are placed in motion by the locomotive or other source of energy.

As a further object of the invention I provide a resilient connection between the end sill or other stationary part of the car and the slideable draw bar shank associated therewith, one end of the resilient connection being secured to the end sill or other stationary part of the car while the opposite end is secured to the slideable draw 20 bar shank.

Another object of the invention resides in the provision of means for the purpose set forth which may be installed in types of cars now commonly in use without dismantling any of the 30 present equipment.

With the above and other objects in view, which will appear as the description proceeds, my invention consists in the novel details of construction and arrangement of parts, described 35 in the following specification and illustrated in the accompanying drawing, and while I have illustrated and described the preferred embodiments of the invention, as they now appear to me, it will be understood that such changes may 40 be made as will fall within the scope of the appended claims.

In the drawing:—

Fig. 1 is a top plan with parts broken away and parts illustrated in horizontal section.

Fig. 2 is a side elevation with parts broken away and parts shown in vertical section; and

Fig. 3 is a fragmental section on the line 3—3 of Fig. 1.

In the well-known forms of draft rigging now 50 commonly used in railway car construction or the like a draft gear spring is used for the purpose of absorbing shock and to lessen or cushion the impacts that occur under the train handling. However, even with the use of a draft gear spring 55 considerable shocks and jars occur because of

uncontrollable slack and it is to overcome this uncontrollable slack and to prevent jars and shocks that I provide novel means to control the draft gear spring resiliency thereby insuring a uniform or flexible movement of the car or cars 5 which are placed in movement by the locomotive or other source of energy. To accomplish this I provide a resilient member having one end secured to the end sill or other stationary part of the railway car while the opposite end is secured 10 directly to the slideable draw bar shank. This resilient member has a tendency to at all times so position the car, with respect to the draw bars, as to prevent any impacts which would cause jar or shock or in other words to balance 15 the position of the car between the draw bar heads at opposite ends of the car. At the present, and in the past, considerable damage has been done to both the railway car equipment as well as the contents of the car due to the uncontrollable slack between the adjacent cars or 20 locomotive which result in heavy impacts which cause shocks and jars. With the use of my invention I have found that any locomotive, and the number of cars attached thereto, may be 25 moved under any and all normal conditions or circumstances entirely free of impacts, shocks, etc., and the entire train is maintained as a flexible unit whereby the locomotive and last car are 30 started, controlled and stopped simultaneously.

In the drawing I have illustrated one well-known form of draft rigging with my improvements associated therewith and it will be understood that the construction will be duplicated at opposite ends of the car. In the construction 35 shown I indicate the longitudinally extending draft sills, secured to the car body in well-known manner, and forming a part thereof, having the longitudinally spaced elongated openings 2, 3 and 4 in which operate the cross keys 5, 6 and 7, 40 the cross key 5 being carried by the draw bar shank 8, the key 6 by the forward follower 9 and the key 7 by the rear follower 10. The usual coupling head 11 is formed on the outer end of the draw bar shank 8 while the inner end of this shank normally bears against the forward end of the follower 9 as shown more particularly in Fig. 1 of the drawing. A draft gear spring 12 is positioned between the followers 9 and 10 to normally hold them in the positions shown in Fig. 1. 50 At 13 I have illustrated connecting links, which act in the same manner as a yoke member, having at their forward ends openings to receive the cross key 5, these openings being of a length equal to the width of the cross key. The links are further 55

provided with the elongated openings 14 and 15 to receive the ends of the keys 6 and 7 respectively as shown more particularly in Fig. 1. As previously stated, the construction so far described is well-known and as the draw bar shank 8 is moved forwardly the cross key 5 will draw on the links 13 and cause the cross key 7 to be moved forward with its follower 10 to compress the draft gear spring 12 between the followers 9 and 10. This will take up shock in a forward direction. When the draw bar shank 8 is moved rearwardly the cross key 5 will be moved rearwardly in the elongated opening 2 and through means of the links 13 move the cross key 6 rearwardly in the elongated openings 3 to cause the follower 9 to be moved rearwardly while the follower 10 is held stationary. The movement will cause the draft gear spring 12 to be compressed and take up shocks in a rearward direction.

20 My invention or improvements consist in a bracket 16 secured to the end sill 17 of a car by means of the nuts and bolts 18, the bracket 19 secured to the draw bar shank 8 by the screws 20 or other suitable fastenings, and the coiled spring 21 interposed between the brackets 16 and 19 with the forward end of the spring secured to the bracket 16 while the rear end of the spring, is secured to the bracket 19. In the drawing I have illustrated a cylindrical member 22, received 30 within the spring 21 to prevent buckling of the spring, but it will be understood that the cylinder may be eliminated without in any way effecting the invention. It will thus be seen that the coiled spring 21 is connected directly to the end sill 35 forming a part of a car while the opposite end is secured to the draw bar shank. The coiled spring 21 controls the draft gear spring resiliency, in a manner to be described, to insure a uniform or flexible movement of the car or cars and to prevent 40 damaging impacts, shocks, etc. While I have illustrated one end of the spring 21 secured to the bracket 16, secured to the end sill 17 forming a part of the car, it will be understood that this end of the spring could be connected 45 to other stationary parts of the car frame or body and the same results obtained.

With the above detailed description I will now endeavor to more clearly bring out the operation of my improvements. It can be readily appreciated that the draft gear springs while tending to take up slack would not prevent damaging impacts of the parts, because the speed and weight of individual cars in the train is not controlled by the draft gear springs under certain 50 and numerous operating conditions, due to the fact that through the coupling 11 the draw bar shank 8 is drawn to move the car to which the draft rigging is connected and permits the draft gear springs to function separately from the car. 55 In other words, the present draw bar connection and draft gear attachment is an indirect connection relative to the position of the draft gear springs to control the speed and weight of individual cars, consequently these springs are free 60 to move in their normal state which is in the direction of the least resistance and thereby accelerate the movement of the car and this uncontrollable slack action gains momentum as it travels throughout the train and contributes to 65 the violence of the impacts. It can readily be seen that my invention provides a coiled spring 21 at each end of the car, fastened at one end to the bracket 16 which is secured to the end sill 17, forming a stationary part of the car, while 70 the opposite end is fastened to bracket 19 which 75

is secured to the slidable draw bar shank. The compression and expansion of the coiled spring 21 depends entirely upon the relative movement of the draw bar shank and the resiliency in coiled spring 21 acts constantly upon the resiliency of the draft gear spring 12 which keeps this spring normal or restores it to its normal position in a gradual way and entirely free of shocks, jars, etc. It will also be seen that my method of attachment establishes a direct connection between the car itself and the slidable draw bar shank to which is connected the draft rigging to make the movement of the car possible and that my method of attachment further provides that during any acceleration of the car that the coiled spring 21 responds instantaneously and forces the draft gear spring to its normal position in a direction opposite to the normal movement thereof and this control of the draft gear spring resiliency maintains the weight and speed of each 20 car throughout the length of the train, consequently the cause for uncontrollable slack action has been entirely eliminated. More specifically assuming that the train is moving forwardly it will be seen that through the coupling 11 the 25 draw bar shank will be drawn forwardly to move the car to which the draft rigging is connected and in this movement the coiled spring 21 will be compressed between the end of the car and the bracket 19 secured to and carried by the draw bar 30 8. During the normal movement of the train there will be, of course, no impacts but when the movement of the car is accelerated relative to the draw bar shanks such as when stopping the train, or when going down hill the car will have 35 a movement relative to the draw bar shank and unless my improvements were provided there will be impacts between the parts such as the engagement of the coupling head with the rigging, the engagement of the cross keys with the ends of 40 their respective slots, etc. With my improvements when the movement of the car is accelerated with respect to the draw bar shank the coiled spring 21, which has been previously compressed, will expand to its normal position and 45 then further movement of the car relative to the draw bar shank will further expand the spring and this expansion will have a tendency to draw the car rearwardly with respect to the draw bar shank and coupling head to restore the parts to 50 their normal position without damaging impacts, shocks, etc. In this movement the corresponding parts of the rigging at the opposite end of the car will be operated and the coiled spring 21 at the 55 opposite end of the car will be compressed with a tendency to expand to move the car rearwardly to assume its normal balanced position between the coupling heads. Assuming that the train is being backed the draw bar shank 8 will be moved rearwardly and the coiled spring 21, at one end of the car, will be expanded. The tendency of the coiled spring will be to return to its normal unexpanded position and this will draw the car rearwardly to prevent impacts with the coupling head and other parts. In this movement the spring 21, at the opposite end of the car, will be expanded and tend to draw the car to a balanced 60 position between the coupling heads of the draw bars. It will be seen that I have provided flexible connections independent of the draft gear spring to balance a car to prevent shocks or impacts such as would damage parts of the car or the contents thereof. 65 70 75

Having fully described my invention what I 75

claim as new and desire to secure by Letters Patent is:—

1. A draft rigging including longitudinally extending transversely spaced side sills, an end sill, a draw bar, longitudinally spaced followers positioned between the side sills, a draft gear spring interposed between the followers, and an auxiliary spring having one end connected to the draw bar and the opposite end connected to the end sill.

2. A draft rigging including longitudinally extending transversely spaced side sills, an end sill, a draw bar, longitudinally spaced followers positioned between the side sills, a draft gear spring interposed between the followers, and an auxiliary ⁵ spring extending parallel with the draw bar and having one end secured to said draw bar and the opposite end connected to the end sill.

WILLIAM WATSON BRINKLEY.
